FRAME SUPPORTING DEVICE

Vladimir W. Herz, New York, N. Y.

Application March 20, 1946, Serial No. 655,750

5 Claims. (Cl. 40—152.1)

1

My invention relates to supporting devices for picture frames and similar devices, and refers particularly to devices of the character described and is so constructed as to prevent a picture or other decorative or instructive sheet of material, positioned between the transparent front of the frame and a backing member from becoming accidentally displaced, this particular feature of my device being accompanied by other valuable attributes which will be readily understood by their descriptions given herein.

The ordinary device of the character to which the devices of my invention appertains comprises a frame-like structure the face member of which is transparent, a removable backing member adapted to maintain a sheet of material against the inner face of the transparent member, and means for accomplishing this abutment. Some of the thus described devices have means adapted to maintain the frame in an upright position when it is placed upon a horizontal surface, such as a table, and it is to the last described devices that the devices of my invention are particularly directed.

The following are among the desirable attributes of devices of the character described:—they should be strong and economic in construction, should be readily released from and attached to the frame in order to allow of the removal from, and insertion into, the frame of desirable sheets of informative value, they should be capable of placement for supporting the frame in vertical position, they should be capable of placement upon the backing member without removal of the frame to allow of convenient packing and of hanging upon a wall, and they should be adapted to force the backing member against the informative sheet of material and the latter against the transparent face of the frame as firmly as possible.

As the usually employed backing material is flexible and bendable, it is evident that a pressure exerted upon its central portion will not produce as firm a fixed position between the informative sheet and the face of the frame as will a pressure upon the outer edge portions of the backing material, and my invention discloses means for accomplishing this desired pressure upon the outer edge portions of the backed material.

The above-mentioned, and other desirable features of the devices of my invention will be evident upon a consideration of my application and its accompanying drawings.

By "folded position" I mean the position of my

2

device when it is revolved against the backing member and by "unfolded position" I mean the position of my device when it is in a plane perpendicular to the plane of the backing member and is adapted to maintain the frame in an erect position when placed upon a horizontal surface.

By the word "frame" I mean any device having a transparent face and adapted to hold a sheet of material and includes frames having a removable sheet of transparent material, as well as those in which the entire device including both the face and the surrounding edge portions are integral with each other and of transparent material.

15 In the accompanying drawings illustrating one form of a device of my invention, similar parts are designated by similar numerals:

Figure 1 is a side elevation of one form of a device of my invention with the device in unfolded position.

20 Figure 2 is a rear view showing in dotted lines the folded position of my device.

Figure 3 is an enlarged section taken on the line 3—3 of Figure 2.

25 Figure 4 is a still larger section taken on the line 3—3 of Figure 2 with the device in folded position.

Figure 5 is a section taken on the line 5—5 of Figure 2 with the device in folded position.

30 The particular form of a device of my invention comprises a rectangular transparent frame 10, having the rearwardly extended end flanges 11, 11, which are inclined slightly inwardly, the flanges 11, 11 having opposed openings 12, 12 for purposes described later.

35 A backing sheet 20 is positioned upon the inner face of the frame 10. This sheet may be of cardboard, wood, metal, synthetic resin or other material having sufficient rigidity, so that when the holding members, described later, are pressed upon it, the entire sheet will have approximately the same pressure upon the entire frame face or upon a picture or sheet of display matter 30 placed between the backing sheet 20 and the face of the frame 10.

40 The above described frame and backing sheet are set forth in order to illustrate one form of these elements suitable for use with my pressure device, described later, but my device is not limited to use with these described elements, but is adaptable for use with other frames and backing sheets.

45 The supporting device of my invention comprises a rod having the member 40 which is extended into the angularly positioned member 41,

which is extended into the angularly positioned member 42, which is extended into the angularly positioned member 43. The free ends of each of the members 40 and 43 have an extended reduced portion 44 adapted to be inserted within an opening 12 of the frame flange 11 and to be revolvable therein.

A concave-shaped pressure member 45 with its concave face positioned toward the backing sheet 20 carries the fixedly attached plate 46, the central portion of which is a semi-circular bearing 47 for the reception of the rod portion 43.

A similar concave-shaped member marked with corresponding prime numerals acts as a bearing for the rod portion 40.

The described supporting device is of such construction and material in order that the stub ends 44, 44 may be readily removed from and inserted into the openings 12, 12 of the frame flange 11, 11.

The rod member portions 40 and 43 of the supporting device are bent or biased inwardly in order that a camming effect will be produced when the supporting device is revolved from folded position to unfolded position, thus forcing the pressure members 45, 45' against the backing sheet 20, as shown particularly in Figs. 2, 3, and 4.

The full lines in Figure 2 show the pressure device in its position when the end portions of the pressure members are pressing against the backing sheet 20.

The dotted lines in Figure 2 show the pressure device in its folded position, that is when the device is revolved within the bearings 47 and 47' against the backing sheet 20.

Assuming that the device is in its folded position as shown in dotted lines in Figure 2 and in Figures 4 and 5, it will be noted that the end portions of the concave-shaped pressure members 45 and 45' rest only lightly upon the backing sheet 20, and are forming no considerable pressure thereon.

It will be noted, however, that when the device is revolved into its unfolded position, as shown in full lines in Figures 1 and 2 and in Figure 3, the pressure members 45 and 45' are moved toward the backing sheet 20 causing their extended portions to be firmly forced against the backing sheet, and that this desired pressure for maintaining the backing sheet 20 and the frame 10 in fixed position with respect to each other is greatly emphasized by the fact that the pressure is exerted upon the side portions of these two elements instead of solely upon their central portions, thus firmly holding these two elements from possible accidental slippage.

It is evident that the concave-shaped pressure members may be of any desired length to accomplish the desired result.

I do not limit myself to the specific size, shape, number, position or material of parts as shown and described as these may be varied without going beyond the scope of my invention.

What I claim is:

1. A frame supporting device, comprising a frame with a transparent face and having opposed backwardly extended flanges, said flanges having aligned openings therein, a supporting member having biased end portions the ends of which are removably carried and revolvable within said flange openings, an intermediate portion of said supporting member being bent to lie in an approximate plane with the lower edge of the frame, a plurality of bearings carried by

said supporting member within which said supporting member is revolvable, and an outwardly extended pressure member carried by each said bearing adapted to produce increased pressure toward said face of said frame in response to said biased end portions as the supporting member is moved from its folded position to its unfolded position.

2. A frame supporting device, comprising a frame with a transparent face and having opposed backwardly extended flanges, said flanges having aligned openings therein, a backing sheet positioned upon the rear face of said frame, a supporting member having biased end portions the ends of which are removably carried and revolvable within said flange openings, an intermediate portion of said supporting member being bent to lie in an approximate plane with the lower edge of the frame, a plurality of bearings carried by said supporting member within which said supporting member is revolvable and an outwardly extended pressure member carried by each said bearing adapted to produce increased pressure against said backing sheet in response to said biased end portions as the supporting member is moved from its folded position to its unfolded position.

3. A frame supporting device, comprising a frame with a transparent face and having opposed backwardly extended flanges, said flanges having aligned openings therein, a supporting rod having biased end portions the ends of which are removably carried and revolvable within said flange openings, an intermediate portion of said supporting rod being bent to lie in an approximate plane with the lower edge of the frame, a plurality of bearings carried by said supporting rod within which said supporting rod is revolvable, and an outwardly extended pressure member carried by each said bearing adapted to be pressed against said face when said rod ends are disposed in said flange openings, said pressure members being adapted to produce increased pressure toward said face of said frame in response to said biased end portions as the supporting rod is moved from its folded position to its unfolded position.

4. A frame supporting device, comprising a frame with a transparent face and having opposed backwardly extended flanges, said flanges having aligned openings therein, a backing sheet positioned upon the rear face of said frame, a supporting rod the ends of which are removably carried and revolvable within said flange openings, camming means adjacent each of said ends of said supporting rod, an intermediate portion of said supporting rod being bent to lie in an approximate plane with the lower edge of the frame, a plurality of bearings carried by said supporting rod within which said supporting rod is revolvable and an outwardly extended pressure member carried by each said bearing adapted to produce increased pressure against said backing sheet as the supporting rod is moved from its folded position to its unfolded position.

5. A frame supporting device, comprising a frame with a transparent face and having opposed backwardly extended flanges, said flanges having aligned openings therein, a supporting member the ends of which are removably carried and revolvable within said flange openings, a portion of said supporting member adjacent each of said ends being biased inwardly to provide a camming action when the supporting member is revolved from one position to another, an

intermediate portion of said supporting member being bent to lie in an approximate plane with the lower edge of the frame, a plurality of bearings carried by said supporting member within which said supporting member is revolvable and an outwardly extended concavo-convex pressure member carried by each said bearing adapted to be pressed against said face when said ends are disposed in said flange openings, said pressure members being adapted to produce increased pressure toward said face of said frame as the supporting member is moved from its folded position to its unfolded position.
